(57) CLAIM

The ornamental design for a boot, as shown and described.

DESCRIPTION

FIG. 1 is a bottom, rear, perspective view of a boot showing our new design;

FIG. 2 is an enlarged view of the area labeled “2” in FIG. 1;
FIG. 3 is a front elevational view of the boot shown in FIG.
1;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines illustrate features of the boot that form no part of the claimed design. The dash-dot-dash lines are used to show an area of enlargement and form no part of the claimed design.
